Primary Examiner — Sheryl Lane*Assistant Examiner* — Ieisha N. Price(74) *Attorney, Agent, or Firm* — Manabu Kanesaka(57) **CLAIM**

The ornamental design for a structural material connection bracket, as shown and described.

DESCRIPTION

1. Structural material connection bracket

1.1 : Front

1.2 : Back

1.3 : Right

1.4 : Left

1.5 : Top

1.6 : Bottom

1.7 : Cross sectional

1.8 : Perspective

1.9 : Perspective

1.10 : Reference cross sectional view shown in its state of use

Fig. 1.7 is a cross sectional view taken along line A-A of Fig. 1.1; Fig. 1.10 is the cross sectional view of Fig. 1.7 shown in its state of use; the structural material shown in broken lines illustrates the environment of the claimed design and forms no part thereof.
